UNITED STATES PATENT OFFICE.

GUSTAF O. JOHNSON, OF ELKHART, INDIANA.

INFANT'S CARRIAGE.

1,346,963.

Specification of Letters Patent. Patented July 20, 1920.

Application filed May 15, 1918. Serial No. 234,662.

To all whom it may concern:

Be it known that I, GUSTAF O. JOHNSON, a citizen of the United States, residing in the city of Elkhart, county of Elkhart, Indiana, have invented certain new and useful Improvements in Infants' Carriages, of which the following is a specification.

My invention relates to infants' vehicles or carriages, and more especially to a steel reinforced frame for a reed carriage for infants.

In carriages of this class the seat side rails are carried by upright post members mounted upon the seat frame or some part of the main carriage frame, the posts being usually set and glued in a shallow socket. This structure is frail and unsatisfactory, for lateral pressure causes the side rails to spread, whereby the rail posts are either loosened or broken off in their sockets.

An object of my invention is the production of a metal reinforcing bracket member for preventing the spreading of the seat side rails, and thereby the posts, of a carriage of the class mentioned herein, whereby breaking of the posts is also prevented or very much reduced. Another object is the production of a reinforcing device of the class described which is provided with a hinge for the swinging seat back. Other objects of my invention are mentioned and described herein.

The preferred embodiment of my invention is well illustrated in the accompanying drawings in which Figure 1 is a side elevation of a seat for a baby carriage of the perambulator type to which my invention is applied; Fig. 2 is a rear elevation of the same seat; Fig. 3 is a section taken on the line 3-3 of Fig. 2; Fig. 4 is a section taken on the line 4-4 of Fig. 2; Fig. 5 is a section taken on the line 5-5 of Fig. 2; Fig. 6 is a section taken on the line 6-6 of Fig. 2 with the seat back shaft omitted; Fig. 7 is a bottom plan view of the seat frame corner, in fragment, showing my invention applied thereto; Fig. 8 is a top plan view of the members shown in Fig. 7; and Fig. 9 is a blank of my invention before its application to a carriage.

Similar numerals of reference indicate similar members and parts of members

throughout the several views on the drawing.

On the drawing, the letter A indicates a seat frame for an infant's carriage which frame may comprise a bottom portion including parallel side members 1, 1 and front and rear transverse members 2, 2 connecting said side members, only the rear transverse member being shown. The frame A may include also a pair of rear post members 3, 3 mounted upright in or upon the side members 1, 1 at 4 adjacent the rear ends thereof. A pair of side rails 5, 5 connect the upper ends of the posts 3 with the forward end of the side members 1. The numeral 6 indicates a swinging seat back carried by member A and which may be composed of a transverse shaft member 7, a pair of upright spaced posts 8, 8 fixed in said shaft, the upper ends of said posts being connected by a transverse member 9. The space within the seat back members may be filled with reed work.

The ends of the shaft 7 preferably project beyond the side posts 8 to serve as journal or bearing members, as hereinafter described. My invention consists of and resides in a combination reinforcing bracket and hinge member 10, a pair of which are used and applied to certain members of the frame A and the rocking seat back 6, in the manner and for the purposes hereinafter described.

The member 10 is composed of a horizontal base portion 11, which is adapted to be fastened to the seat base, and the upright arm section 12 which is adapted to be fastened to the post 3 for reinforcement thereof. The member 10 is made of any suitable ductile metal, preferably of sheet steel, of sufficient weight to possess considerable rigidity when bent into the final form, as hereinafter described. Numerals 13, 13 indicate a plurality of top fastener lugs, and numerals 14, 14 indicate a plurality of bottom fastener lugs, all of said lugs being integral with member 11 of bracket 10 and projecting therefrom substantially at right angles. Numerals 15 and 16 indicate top and bottom lugs, respectively, formed integral with member 11 adjacent the base of the arm 12, integral with portion 11

and extending substantially at right angles thereto, being relatively shorter than the fastener lugs 13 and 14. The arm 12 may extend from member 11 at substantially right angles or otherwise at a somewhat different angle to accord with any desired lateral inclination of the rear posts 3, 3.

Numerals 17, 18, 19 and 20 indicate two pairs of coöperating fastener or clamping lugs integral with the arm 12 and extending substantially at right angles thereto, of which the lugs 18 and 20 may be somewhat shorter than lugs 17 and 19. Numeral 21 indicates a hinge lug integral with bracket member 11, extending therefrom at substantially right angles from the top edge thereof and substantially parallel with the lugs 13, being located intermediate a lug 13 and the lug 15. Hinge lug 21 may be ribbed or corrugated longitudinally thereof as at 22 for reinforcement thereof. Each of the fastener lugs 13 is provided with a bur 23 formed thereon by any suitable punch or pointed tool. The lugs 14, 14 are provided with similar burs 24, said burs being adapted to be pressed into the wood of the seat base members for confining and securing the member 10 thereto, whereby nails, screws, or other fastener members are dispensed with.

In the application of my invention, the lugs 13, 13, 14, 14, 15 and 16 are first bent over at an angle somewhat less than ninety degrees, as a preliminary formation thereof, and the hinge lug 21 on one of the members 10 is bent into its ultimate semicircular form, as indicated in Fig. 5. The second member 10 is operated upon in the same manner except that the hinge lug 21 thereof remains unbent. Both members 10 are thereupon fastened in position at opposite sides of the frame A by pressing the lugs 13, 13, 14 and 14 against the wood members 1 and 2, or either of them, thereby forcing the lug burs 23 and 24 into the wood of said members, and simultaneously pressing the lugs 15 and 16 into close contact with the upper and lower surfaces of frame member 1, whereby a rigid fastening is effected. In this position of member 10 the arm 12 thereof lies parallel and continuous with the upright post 3. The lugs 17, 18, 19 and 20 are thereupon bent around and rigidly pressed upon the exterior of the post 3. Thereupon one end of the seat back shaft 7 is inserted in the semicircular hinge lug 21, assuming that both brackets 10 have been fastened to the seat base as described, and the second hinge lug 21 is bent into a semicircular formation around the opposite end of the shaft 7 and with some play to enable the shaft end to be rotated therein. In Figs. 7 and 8 the lugs 13, 13, 14 and 14 are shown engaging only the frame member 2, but the joint between members 1 and 2 may

be placed between the lugs 13, 13 and 14, 14, as indicated by the dotted line designated by the numeral 25, whereby said joint is reinforced and the frame base stiffened materially.

In the manner described the frame posts 3, 3 are greatly reinforced by the arm 12 of the member 10, whereby spreading thereof is prevented and the possibility of a breakage thereof in the post socket 4 greatly reduced. While I show my invention applied to a seat back and seat of a perambulator type of infant's vehicle, it may be and is readily applied to the main frame and swinging seat back of a four wheeled cab, the Figs. 1 and 2 being shown to merely illustrate one application of the invention.

I claim:

1. In combination with the frame and swinging seat back of a vehicle, a reinforcing member having a base portion and a post section extending angularly therefrom, said base portion being adapted to be fastened to a transverse member of said frame, and said post section being adapted to be fastened to an upright member connected with said frame, and a hinge member projecting from one portion of said reinforcing member and adapted to serve as a bearing member for said swinging seat back.

2. In combination with the frame and swinging seat back of a vehicle, a reinforcing member having a base portion and a post section extending angularly therefrom, said base portion being adapted to be fastened to a transverse member of said frame, and said post section being adapted to be fastened to an upright member connected with said frame, and a hinge member projecting from said base portion of the reinforcing member and adapted to serve as a bearing member for said swinging seat back.

3. In combination with the frame and swinging seat back of a vehicle of the class described, a sheet metal reinforcing member having a base portion and a post section extending angularly therefrom, said base portion having a plurality of lugs adapted to be fastened to a transverse member of said frame, said base portion being provided also with a lug adapted to serve as a hinge or bearing member for said swinging seat back, and said post section having a plurality of lugs adapted to be clamped upon an upright member connected with said frame transverse member.

4. In combination with the frame and swinging seat back of a vehicle of the class described, a sheet metal reinforcing member having a base portion and a post section connected therewith and extending angularly therefrom, said base portion having a plurality of lugs adapted to be fastened to a transverse member of said frame, said base portion being provided also with a

bent lug adapted to serve as a hinge or bearing member for said swinging seat back, said base portion being provided also with a pair of relatively short clamping lugs intermediate said hinge lug and said post section, and said post section having a plurality of lugs adapted to be clamped

upon an upright member connected with said frame transverse member.

In testimony whereof I have hereunto affixed my signature this 13th day of May, 1918.

GUSTAF O. JOHNSON.
